Artist

UNITED STATES PATENT OFFICE.

GUSTAVUS E. TAFT, OF WHITINSVILLE, MASSACHUSETTS.

YARN-SEPARATING DEVICE FOR SPINNING-MACHINES.

SPECIFICATION forming part of Letters Patent No. 365,155, dated June 21, 1887.

Application filed December 31, 1886. Serial No. 223,098. (No model.)

To all whom it may concern:

Be it known that I, GUSTAVUS E. TAFT, of Whitinsville, in the county of Worcester and State of Massachusetts, have invented certain new and useful Improvements in Yarn-Separating Devices for Spinning - Machines, of which the following is a full, clear, and exact description, reference being had to the accompanying drawings, forming part of this specification.

This invention relates to a separator-plate mechanism, or an apparatus for operating separator-plates or thread-guards in spinning-machines.

In spinning - machines it is desirable to place the spindles as close together as practicable, so as to get the largest possible number in one machine and under the control of one operator. With the increase of the speed with which the modern spindles are run the centrifugal force throws the yarn farther from the spindle than when low speed has been used, and the globe or balloon described by the yarn between the guide-wire and the traveler on the ring is increased in diameter. Under these conditions partitions or separators placed between the adjacent spindles have become a necessity, and the arrangement by which such separators have heretofore been secured to and carried by the ring or traverse rail is objectionable, as it increases the weight of the ring-rail and obstructs the free access to the cop or bobbin in piecing or doffing. The longer the distance between the guide-wire and the traveler the larger will be the balloon or the farther will the yarn be thrown out, while when the ring-rail is raised and is nearing the guide-wire the shorter yarn between the guide-wire and traveler will not balloon any more than is required to clear the cop or bobbin.

One object of my invention is to provide a series of separator-plates, which are automatic and positive in action.

Another object of my invention is to adapt a separator-plate mechanism to a double form of spinning-machine, and which will be actuated by a single cam.

Another object of my invention is to render the operations of the mechanism easier by the use of counter-balances for these separator-plates.

To the above purposes, my invention con-

sists in particular combinations, set forth in the claims at the close of this specification, and which comprise the following devices: the separator-plates, the plate-shafts, a counter-balance, slotted operating-levers for the plate-shafts, a pivoted and a slotted rocker, a connecting-rod, a cam-bar and a cam, a counter-weight having a rope-and-pulley connection, and the hangers for the plate-shafts.

In order that my invention may be fully understood, I will now proceed to describe the same in reference to the accompanying drawings, which illustrate the best form thereof so far devised by me, and which form admits of various modifications in the details.

In the accompanying drawings, Figure 1 represents a vertical sectional view of an ordinary double form of spinning-machine, showing the side framing, and in which is embodied my improved separator-plate mechanism. Fig. 2 represents an enlarged broadside view of one of my separator plates and a counterpoise, both mounted upon the plate-shaft shown in section. Fig. 3 represents a top plan view of Fig. 2, partly broken away.

In the said drawings like numbers of reference designate corresponding parts throughout.

Referring to the drawings, 6 designates part of the framing of an ordinary form of spinning-machine having a double system of spindles, 7, which are rotated in the usual manner by means of the main shaft 8. The traversing-ring or traverse-rail 9 is provided with the rings 10 for the ordinary travelers (not shown) and is moved up and down by well-known mechanism, which is here omitted, and serves to control the building of the yarn 11 upon the cops or bobbins placed upon the spindles. The guide-wires 12 are secured to the guide-blocks and are located one above each spindle.

In order to prevent the interference of the spread-out yarns running to adjacent spindles, I have devised the following mechanism, which renders the aforesaid evil impossible. The plate-shaft 13 is mounted and turns in the hangers 14, secured to the machine-frame. The separator-plate 15 is formed with a broad flat body of the shape shown, and is provided with a shank having a transverse perforation, 16, to receive the plate-shaft. In the recess

17, at the end of the shank, is arranged the set-screw 18, which extends into the perforation 16 and binds upon the plate-shaft to hold the plate in position when adjusted. By this 5 countersunk end of the shank of the plate the set-screw 18 is entirely concealed and cannot catch in foreign objects. The plate-shaft is formed with the flat face 19, and the perforations 16 of the plates conform thereto, so that 10 all the plates may be maintained in the same position relative to the horizontal plane, though they may be adjusted sidewise along the plate-shaft, as desired. The operating-lever 20 is formed with a slot, 21, and is rigidly 15 secured upon the plate-shaft 13, so that by depressing and elevating the lever the plate-shaft may be turned in its bearings, and thereby vibrate the attached separator-plate in a vertical plane. The operating-levers are actuated 20 by the pivoted rockers 22 and 23, which are each provided with a fixed stud, 24, working in the slots 21 of the operating levers, and which are each pivoted to the machine-frame at the points 25. These rockers are hinged 25 together by the inner ends at the point 26, so that when one of the rockers is rocked both of them will vibrate in unison in the vertical plane. By virtue of the play in the two hinged joints 25, together with that of the 30 hinged joint 26, the rockers are permitted to freely move through the required space and to pass without jar the central point between the full and dotted line positions, respectively. However, to insure the smooth working of 35 the rockers, if preferred, the rocker 23 may be formed near its inner end with the slot 50 for the hinge-pin of the joint 26 to move in as the rockers oscillate. The rockers are operated by means of the connecting-rod 27, which 40 is provided with a pin, 28, which pin takes in the slot 29, formed in the rocker 22. The object of having the pin 28 take through the slit 29 is to afford means for tightening up the cam-bar against the cam, and the pin after being set remains immovable in the slot. To 45 the foot of the rod 27 is pivoted the cam-bar 30, which is hinged to the post 31. The post 31 is vertically adjustable by virtue of the slot 32 and the binding-screw 33, which holds the 50 post to the machine-frame.

The cam 34 is keyed on the cam-shaft 35, which is mounted in the machine-frame, and may be driven in any suitable manner by connection with the main shaft 8. This cam is so 55 arranged that at every revolution of the same the rockers are moved down and up again on their pivots, and this indirectly moves the separator-plates from the horizontal position into the vertical position, which is shown in 60 dotted lines, and back again through the quadrant of a circle.

It is necessary to have the cam-bar in constant engagement with the cam, and to accomplish this I provide the rocker 23 with a 65 counter-weight, 36, to which is fastened a rope or cable, 37, which is passed over a pulley, 38, fixed to the machine-frame, and the other end

of the rope is secured to a link connected to the rocker 23. This weight 36 serves to hold the rocker 23 in the upper position; likewise 70 the rocker 22, which, by means of the connecting-rod 27, keeps the cam-bar in engagement with the cam.

I find that the working of the entire mechanism is much improved and rendered easier 75 in operation by providing counter-balances 39, for counterbalancing the weight of the separator-plates, as shown in Figs. 2 and 3. These counter-balances are formed with an eye, 40, to receive the plate-shaft, upon which they are 80 mounted and held by the set-screw 41, which is arranged similar to the set-screw 17 of the plates. The counter-balance 39 is disposed in an opposite manner to the plates, as shown, and any number of them may be used to gain 85 the required balance.

From the foregoing description the following operation of my improved mechanism will be readily understood. The traversing-ring or traverse-rail 9 is at the lowest limit of 90 travel; likewise are the separator-plates 15 at the lowest limit of vibration. The relative movements of the ring or traverse rail and the plates are synchronous, and are gaged so that as the ring-rail starts upward the cam begins 95 to draw down the rocker, and thereby to elevate the separator-plates, which continue to move about the axis of the plate-shaft while the ring-rail moves upward, and until the vertical dotted-line position is reached, when the ring-rail, having arrived at the upper limit of travel, stops and then descends. Then the counter-weight 36 acts to reverse the rockers by depressing them, and this lowers the separator-plates, which follow down after the descending ring-rail, and these simultaneous 100 movements are repeated by the running of the machine.

By virtue of my improved mechanism the broadsides of the separator-plates are always 110 held parallel with the axes of the spindles, and the plates are automatically moved in unison with the rise and fall of the ring or traverse rail, the plates being always out of contact with the ring-rail.

An important advantage of my invention is 115 that the ring-rail is not encumbered with the separator-plates, which are moved into vertical position when the ring-rail is at the upper limit, so as to clear the rail and to be out 120 of the way of the bobbin or cops in doffing, and to give better access to the spindles in piecing up the yarn.

It is to be observed that in using my improved mechanism with a spinning-machine 125 having the spindles upon one side only, one of the rockers is of course omitted, and in this case the counter-weight 36, for holding the rockers in the upward position, is placed upon the rocker with which the connecting-rod 27 is connected, in order to operate the mechanism, as hereinbefore described.

Having thus described my invention, I claim 130 as new and desire to secure by Letters Patent—

1. The combination, with the framing, a set of spindles, and a ring or traverse rail, of a series of separator-plates, a turnable plate-shaft upon which said plates are mounted, a counter-balance for said plates, an operating-lever secured upon said plate-shaft, a rocker engaging said lever, a connecting-rod attached to said rocker, and a cam-bar connected to said rod, a cam engaging said cam-bar, and means, substantially as described, for holding said cam-bar in engagement with said cam, whereby the cam may indirectly vibrate the separator-plates, as and for the purpose herein described.

2. The combination, with the framing, a set of spindles, and a traversing ring or traverse-rail, of a series of separator-plates, a turnable plate-shaft for said plates, a slotted operating-lever secured upon said plate-shaft, a pivoted rocker provided with a stud working in the slot of said operating-lever, a connecting-rod attached to said rocker and a hinged cam-bar connected to said rod, a cam engaging said cam-bar, and means, substantially as described, for maintaining said cam-bar in engagement with the cam, whereby the revolutions of the cam may serve to vibrate the separator-plates, as and for the purpose herein described.

3. The combination, with the framing and a set of spindles, of a series of separator-plates, a turnable plate-shaft for said plates, a slotted operating-lever secured to said plate-shaft, a pivoted slotted rocker provided with a stud engaging the slot in the operating-lever, a connecting-rod provided with a pin working in the slot of said rocker, a hinged cam bar connected to said rod, and a cam engaging said cam-bar, a counter-weight or equivalent connected with said rocker for holding the cam-bar in engagement with said cam, substantially as herein described.

4. The combination, with the framing, the spindles, and traversing ring or traverse-rails, of a series of separator-plates, a set of plate-shafts provided with slotted operating-levers, a set of rockers independently pivoted and hinged together in pairs and provided each with a stud working in the slot of an operating-lever, one of said rockers provided with a connecting-rod, and a cam-bar connected to said rod, and a cam-engaging said cam-bar, one of said rockers provided with a counter-weight attached thereto for holding the cam-bar in engagement with said cam, substantially as herein described.

5. The combination, with the framing, the spindles, and ring or traverse rails, of a series of separator-plates, a set of plate-shafts for said plates, slotted operating-levers secured to said shafts, a pair of rockers independently pivoted and hinged together, and each provided with a stud working in the slot of one of said operating-levers, one of said rockers formed with a slot and a connecting-rod provided with a pin working in the slot of said rocker, a cam-bar pivoted to said rod, and a cam engaging said bar, the other said rocker

provided with a counter-weight for drawing said rocker up, substantially as herein described.

6. The combination, with the framing, the spindles, and ring or traverse rails, of a series of separator-plates, the turnable plate-shafts provided with the counter-balances and slotted operating-levers, the independently-pivoted rockers hinged together and each provided with a stud working in the slot of one of said operating-levers, one of said rockers formed with a slot, and a connecting-rod provided with a pin working in said slot, a cam-bar pivoted to said rod, and a cam engaging the bar, the other said rocker provided with a counter-weight having a rope-and-pulley connection, substantially as herein described.

7. The combination of the framing and the spindles, the ring or traverse rails, a series of separator-plates, the plate-shafts provided with hangers mounted on the frame, the slotted operating-levers secured to the plate-shafts, the independently-pivoted rockers hinged together, the connecting-rod and hinged cam-bar secured thereto, the cam engaging the cam-bar, the counter-weight and the pulley fixed to the frame, and the rope intermediate of the rocker and counter-weight, substantially as herein described.

8. The combination, with the separator-plates and plate-shafts, the framing and the rockers hinged thereto, connections intermediate of the rockers and the plate-shafts, and the connecting-rod attached to one of said rockers and to the cam-bar, of the cam, the cam-bar engaging said cam, the adjustable post provided with the slot, the binding-screw taking in said slot and attached to the machine-frame, the connecting-rod, and the rocker, substantially as described, whereby the bearing of the cam-bar against the cam may be regulated.

9. The combination, with the framing, a set of spindles, and a traverse or ring rail, of a series of separator-plates, 15, the turnable plate-shaft for said plates, the slotted operating-lever 20, the pivoted rocker 22, the connecting-rod 27, and the hinged cam-bar 30, secured thereto, the cam 34, engaging said cam-bar, and means, substantially as described, for holding the cam-bar in engagement with the cam, substantially as herein described.

10. The combination, with the framing, the spindles, and a ring or traverse rail, of a series of the separator-plates 15, the turnable plate-shaft 13, supported upon the machine-frame, the slotted operating-lever 20, the pivoted rocker 22, provided with the slot 29 and the fixed stud 24, the connecting-rod 27, provided with pin 28, working in said slot 29, the hinged cam-bar 30, pivoted to said rod, the cam 34, engaging the cam-bar, and means, substantially as described, for holding said bar in engagement with said cam, substantially as and for the purpose described.

11. The combination, with the framing, the spindles, and the traversing ring or traverse-

- rails, of the series of separator-plates 15, the turnable plate-shafts 13 for said plates, the slotted operating-levers 20, the pivoted rocker 22, provided with the stud 24, the pivoted rocker 23, provided with the stud 24 and hinged to rocker 22, and provided with the counter-weight, the connecting-rod 27, the hinged cam-bar 30, and the cam 34, engaged thereby, substantially as herein described.
- 10 12. The combination, with the framing, the spindles, and the traversing ring or traverse-rails 9, of the series of the separator-plates 15, the turnable plate-shafts 13 for said plates, the slotted operating-levers 20, the independently-

pivoted rockers 22 and 23, provided each with 15 a stud, 24, and hinged together, the connecting-rod 27, and the hinged cam-bar 30, pivoted thereto, the cam 34, engaging said bar, the counter-weight 36, provided with rope 37, and the pulley 38 for said rope, all substantially 20 as herein described.

In witness whereof I have hereunto set my hand.

GUSTAVUS E. TAFT.
